G. E. MILLER

SEAM PRESSING MACHINE

Filed Oct. 6, 1927

UNITED STATES PATENT OFFICE.

GERVASE E. MILLER, OF DANVERS, MASSACHUSETTS, ASSIGNOR TO IDEAL BABY SHOE COMPANY, INC., OF DANVERS, MASSACHUSETTS, A CORPORATION OF MASSACHUSETTS.

SEAM-PRESSING MACHINE.

Application filed October 6, 1927. Serial No. 224,424.

This invention relates to a seam pressing machine and although capable of general application is more especially designed with reference to work on infants' and children's 5 shoes.

In the manufacture of soft shoes or sandals for infants and children, the shoes are first formed by stitching the parts together wrong side out and when fully formed are then 10 turned right side out. Before being turned, however, the edges at the seams are pressed or flattened out in order to remove any ridges on the inside of the shoe and to smooth the exterior at the seams. The small size of the 15 shoes generally offers difficulties in the seam pressing operation especially at the toe portions and the accomplishment of this work has heretofore been attained by hand work which has not been entirely satisfactory in its 20 results in addition to being open to the objections of the time and expense involved.

The main object of the invention is the provision of a simple and efficient machine for operating on work of the foregoing character.

This end is attained by providing a machine having a work-supporting member of small diameter adapted for insertion in a very small shoe and for reaching into the toe 30 portion thereof and which has a clear and unobstructed space therearound permitting the work to be freely moved on the work-supporting member.

Another object of the invention is the provision of a machine which may be operated at a comparatively high speed in order that the work may be performed rapidly and at a low cost.

To this end a hammer is provided having a 40 short stroke and so mounted that it may be reciprocated with great rapidity and effectiveness.

A further object is the provision of means for adjusting either the work-supporting 45 member or the hammer or both to vary the pressure exerted by the hammer and to conform to varying conditions of thickness in the work.

Other objects of the invention will be more 50 specifically set forth and described herein-after.

In the drawings illustrating one embodiment of the invention, Figure 1 is a side elevation of a machine constructed and adapted to be operated in accordance with my invention; Fig. 2 is an elevation looking from right to left in Figure 1 of the portion of the frame of the machine carrying the work-supporting member and showing said member, partly in section, and the hammer; Fig. 3 is a top plan view of the crank-arm end of the hammer lever; Fig. 4 is a sectional view of a portion of a shoe part showing the seam before being pressed and flattened and Fig. 5 is a side elevation of the cooperating parts of the 60 work-supporting member and hammer with work interposed and being pressed.

Referring to the drawings, 10 designates a base portion having at one end an upwardly extending head 11 in the form of a yoke, the 70 two ends of which are extended laterally over the base, in the form of arms 12, and at the other end an end-plate 14 is secured to the base by bolts 16. The end-plate extends below the base and has fastened to its lower 75 portion by bolts 18 a short arm or bracket 20 for carrying the work-supporting member. The flange 22 of the base may be bored to receive screws for mounting the machine on a table or other suitable support and the end-plate extends below the table to hold the 80 work-supporting member at a convenient height for the operator. The frame of the machine, however, may be made in any suitable form.

The operating instrumentalities comprise a work-supporting member 24 and a hammer 26, the former being carried by the arm 20 and the latter by an arm or lever 28. The work-supporting member is in the form of a spindle having a rounded work-supporting end 30 and is mounted upright in a recessed headed stud 32 carried by a sleeve 34 threaded through the end of the arm 20. By turning the sleeve the spindle may be adjusted 90 vertically and for this purpose the head of the sleeve is provided with radial holes 36 for receiving a turning pin.

The hammer 26 is mounted in the end of the arm or lever 28 and may be of any suitable form but as shown comprises a threaded shank 38 having one end expanded to form

the head 26 adapted for pressing the work on the end of the spindle 24. The shank of the hammer may be threaded through the lever 28 or may be mounted loosely therein and secured in fixed position by a nut 40 and set-nut 42.

For reciprocating the hammer, the hammer lever is pivotally mounted midway on a transverse shaft 44 rotatably mounted in 10 bearings 46 formed in the ends of the two arms 12. The shaft is secured against longitudinal movement in the lever and bearings by a set screw 48 which fastens it in the lever. For oscillating the hammer lever, it 15 is connected in any suitable manner to a crank-shaft 50 rotatably mounted in the yoked head 11 having fixed to one end a belt pulley 52 adapted to be driven from any suitable source of power. The crank-shaft has 20 midway a reduced portion 53 which is eccentric to the main axis of the shaft and a pair of bearing blocks 54 are slidably mounted between two rearwardly extending arm portions 56 of the hammer lever for connecting it to the crank portion 53 of the crank shaft. As the crank-shaft is rotated, the movement 25 of the crank arm portion 53 operating as a crank arm, oscillates the hammer lever and the bearing blocks 54 slide longitudinally 30 the lever on guideways 58. For holding the bearing blocks in sliding position and in engagement with the crank arm portion 53, the two arm portions 56 may be connected together by a bolt 60 and nut 62 and the lever 35 may be slotted longitudinally at 64 to permit the two arm portions 56 to be drawn together. The lever may in addition be bored transversely the slot 64 for receiving a threaded bolt 66 and the bore on the lower side of the 40 slot be threaded for drawing the two portions of the rear end of the lever together. A set nut 68 holds the bolt in adjusted position.

In the use of the illustrated machine adjustment is first made to secure the exact pressure desired in view of the condition of the work to be operated upon. Preferably, 45 this is done by turning the headed sleeve 34 to raise or to lower the work-supporting member in relation to the hammer. After the adjustments have been made the work is placed upon the work-supporting spindle and held by the operator and the machine started. The rotation of the crank-shaft oscillates the hammer lever and the hammer pounds down 50 the seam. In Figure 5 is shown a portion of a shoe 70 arranged on the work-supporting spindle in position for pressing down a seam at the heel. The condition of the seam before being operated upon is shown in Figure 4 in 55 which 72 indicates the seam stitching and 74 the two seam edges of material. In the pressing operation, the hammer pounds down the two edges 74 thereby opening up said edges and turning them back each upon its own 60 material.

The operator positions the work upon the spindle as shown in Fig. 5 to bring the seam under the centre of the hammer and then moves it so that the hammer works along each seam. With a rapid vibration of the hammer 70 the work can be accomplished very quickly and efficiently.

It will be observed that there is a clear and unobstructed space around the work-supporting member which greatly facilitates the 75 progress of the work by permitting free handling and movement thereof which is of importance especially when shoes are being operated upon in the toe portions. By employing a work-supporting member in the form of 80 a spindle every portion of a shoe may be easily reached.

Although the embodiment of the invention hereinbefore described was designed with special reference to work on small objects 85 such as infants' shoes yet the machine is capable of general use for seam pressing and the invention is not to be limited to the specific form shown since it may be embodied in other forms without departing from the 90 spirit thereof.

What I claim is:

1. In a seam pressing machine, the combination of a frame, a relatively slender spindle having a semi-spherical end for supporting the work and a reciprocating hammer for pressing and flattening the seam in the work. 95
2. In a seam pressing machine, the combination of a frame, an upright relatively slender spindle having a semi-spherical end for supporting the work and a reciprocating hammer for flattening the seam in the work. 100
3. In a seam pressing machine, the combination of a frame having a main body portion and a relatively lower front portion, an upright relatively slender spindle adjustably mounted in said relatively lower portion of said frame, the top end of said spindle being rounded for supporting the work, and a reciprocating hammer for flattening seams in 105 the work. 110
4. In a seam pressing machine, the combination of a frame comprising a body portion, a front end plate and a spindle carrying arm or bracket secured to the lower end of said front plate below said body portion, an upright spindle adjustably mounted in said arm or bracket and adapted to project into and support an infant's shoe and having a clear and unobstructed space therearound to permit free movement of the shoe on the spindle and a reciprocating hammer for flattening 115 seams in the work. 120
5. In a seam pressing machine, the combination of a frame comprising a body portion, a front end plate and a spindle carrying arm or bracket secured to the lower end of said front plate below said body portion, an upright relatively slender spindle adjustably mounted in said arm or bracket and adapted 125 130

- to project into and support a shoe and having a clear and unobstructed space therearound and a pivotally mounted reciprocating hammer for flattening seams in the work supported on said spindle.
6. In a seam pressing machine, the combination of a frame having its front end at a relatively lower level than its main body portion, an upright work-supporting member adjustably mounted in said front depressed end of said frame and being of a diameter sufficiently small to project into the toe portion of an infant's shoe and having a clear and unobstructed space therearound and a hammer for flattening the seams in the work on said member.
7. In a seam pressing machine, the combination of a frame, an upright vertically adjustable work-supporting member having a semi-spherical end and being of restricted diameter to permit insertion in the toe portion of an infant's shoe and having a clear and unobstructed space therearound to permit free movement of a shoe on said member
- and a reciprocating hammer for flattening the seams in the work on said member.
8. In a seam pressing machine, the combination of a frame comprising a body portion and an overhanging yoke portion, an end plate secured at its upper end to the front of said body portion and an arm or bracket at the lower end of said plate and extending in a forward direction, said arm or bracket being relatively lower than said body portion, an upright vertically adjustable relatively slender work supporting spindle having an upper semi-spherical end and mounted in said arm or bracket at a sufficient distance from the body portion of said frame to give a clear and unobstructed space around said spindle to permit of free movement of an infant's shoe thereon and a reciprocating hammer mounted in said yoked portion of said frame for flattening the seams in the work on said spindle.

In witness whereof, I hereunto set my hand this third day of October, 1927.

GERVASE E. MILLER.
